AUTOMATIC LOCK SLIDER

Louis H. Morin, Bronx, N. Y.

Application December 20, 1946, Serial No. 717,452

11 Claims. (Cl. 24—205.14)

1 This invention relates to sliders for separable fastener stringers. Still more particularly, the invention deals with a lock slider construction having a swivel pull for actuating the lock element of the slider, and means suitable for detachably mounting ornamental or characterizing members therewith. The novel features of the invention will be best understood from the following description when taken together with the accompanying drawing, in which certain embodiments of the invention are disclosed, and in which the separate parts are designated by suitable reference characters in each of the views, and in which:

Fig. 1 is a sectional view through a slider made according to my invention, showing the lock element of the slider in operative position in full lines, and in inoperative position in dot-dash lines.

Fig. 2 is a side view of the structure shown in Fig. 1, with parts in a different position; and

Fig. 3 is an exploded perspective view showing the several parts of the slider detached.

In lock sliders of the kind under consideration, it has been customary to couple the pull on a fixed pivot to swing in the path of movement of the slider along the stringers and in some instances, the lock element of the slider has formed an integral part of the pull.

With my present slider construction, the pull has a rotatable mounting on the slider or on a turret portion of the lock element of the slider so that the chain or other fingerpiece portion of the pull can be swung to either end portion of the slider in operation thereof along the stringers. The lock element has a pivotal mounting on the slider with tensional means normally supporting the lock pin or finger of the element in operative position.

In the drawing, 10 represents a slider body having top and bottom walls 11 and 12 joined centrally at one end by a connecting web 13 having a recess 14 in the upper surface of the top wall 11. The slider is generally of the contour illustrated in Fig. 3, and the top and bottom walls 11 and 12 have inwardly extending side flanges 15 and 16 respectively, defining the channel 17 of the slider. The top wall 11 of the slider has an elongated aperture 18 opening into the channel 17 and centrally of the slider is an upstanding pivot pin 19, preferably made integral with the wall 11, the pin having a reduced upper end 20 which forms a shoulder, as at 21.

Considering Fig. 3 of the drawing, the slider comprises other parts which will be generally

classified as follows. At 22 is shown a coil spring which seats and operates in the recess 14, and at 23 is shown a washer seated on the shoulder 21 of the reduced portion 20 and held thereon by riveting over the top of the reduced portion, as seen at 24, note Fig. 1. The washer 23 holds a lock element 25 in position upon the post 19 or against displacement therefrom. The element 25 has a tubular turret portion 26 grooved, as seen at 27, to receive a split ring 28, the latter retaining a pull 29 against displacement from the lock element 25 while permitting the pull to rotate freely around the turret 26. The upper or open end of the turret preferably has a closure applied to it, and this closure may conveniently serve as an anchor for a detachable ornament. As illustrated, the turret closure, marked 30, takes the form of a socket member of any desired form, similar to conventional socket members of snap fasteners. At 31 is shown a characterizing member having centrally of its lower face a spring studded part 32 for snap engagement with the socket 30 in detachably coupling the member 31 therewith.

Returning now to the lock element 25, this element has at the periphery thereof a downwardly directed pin or finger 33 which operates in the aperture 18 in engaging the scoops of stringers to lock the slider against movement along stringers in the direction of the arrow 34, note Fig. 1.

In Fig. 1 of the drawing I have diagrammatically illustrated in dot-dash lines at 35, scoops of a stringer 36. As fasteners of the kind under consideration are well known in the art, it is not deemed necessary to show the assemblage on stringers.

The lock element 25 has within the turret 26 a large recess or socket 37 in which the washer 23 and pin end 20—24 are arranged, as well as the socket 30, the socket 30 being held in position by seating upon a shoulder 38 in the recess 37 and by peening or riveting over the upper end of the turret, as seen at 39 in Fig. 1 of the drawing. The lock element 25 is so coupled to post 19 that it is free to seesaw back and forth between the full and dotted line positions indicated in Fig. 1. In the construction illustrated, the lower portion of the lock element 25 has centrally of the recess 37 an oversize and preferably conical aperture 40, note Fig. 1, and on opposed sides of the aperture 40, the lock element 25 has rounded projections 41 adapted to seat upon the wall 11 to facilitate pivotal or rocking movement of the lock element, as indicated in full and

3

dotted lines in Fig. 1, the conical aperture 40 permitting the swinging movement of the lock element, as will be apparent. The pull 29 has an extending part 42 apertured as seen at 43, for the reception of a chain or other fingerpiece portion, as indicated at 44 in Fig. 1 of the drawing.

The upper surface of the turret 26 has a key recess 45 adapted to receive a key element 46 on the member 31 to retain said member in 10 predetermined position upon the turret, particularly when the member 31 has, as a characterization, an initial as at 47 to maintain this initial in proper alignment upon the slider at all times.

Considering Fig. 1 of the drawing, it will appear that the spring 22 bears upon the lower surface of the lock element and serves to normally maintain the pin or lock part 33 in operative position. Considering Fig. 3 of the drawing, it will appear that the pull 29 is substantially in the 20 form of a ring having a large aperture 48, which fits freely around the turret to provide for the swinging or rotary movement of the pull on the turret.

By providing the snap fastener socket or similar attaching member in the turret portion of the lock element, characterizing members having stud parts or similar couplings may be detachably mounted in connection with the slider. This is extremely desirable from a sales stand-point, where numerous characterizing members may be employed and attached to the slider upon the sale of the fastener or the garment to which the fastener is attached. Aside from employing ornamental characterized members, the members may simply have one or more initials to personalize the fastener part, garment or article to which the fastener is attached. The latter adaptation of the invention is particularly desirable when fasteners are employed in conjunction with luggage, briefcases and the like, and on various types and kinds of wearing apparel, including pocketbooks and cases of various kinds and classes.

It will also be understood that my invention lends itself to the application of symbols or emblems identifying clubs, fraternal organizations and the like. Most of the parts of the complete fastener can be formed as die castings in metal or plastics, or combinations of metal and plastic, thereby materially simplifying the cost of producing the complete slider. It is here also well to state that proportional sizes, as illustrated in the accompanying drawing, are exaggerated for sake of clarity in the illustration.

It will be apparent that in operating the slider along the stringers to couple the stringers, that is to say, in movement in the direction of the arrow 34, the fingerpiece or pull 29 raises the lock element 25 to withdraw the finger 33 from the channel 17. However, in movement of the slider in the opposite direction to uncouple the stringers, the finger 33 ratchets over the scoops against the action of the spring 22.

Having fully described my invention, what I claim as new and desire to secure by Letters Patent is:

1. A lock slider for separable fastener stringers, said slider comprising a channelled body having spaced walls joined at one end in a connecting web, one wall of the slider having centrally thereof an outwardly extending pivot pin, said wall in spaced relation to the pin having an aperture opening into the channel of the slider body, a lock element pivotally enclosing and

covering said pin, said element having a finger extending through the aperture to enter the channel of the slider, tensional means engaging the lock element to normally support the finger in the channel, said lock element having an outwardly extending turret portion into which said pin extends, a pull rotatably mounted on the turret portion in operating the slider in two directions on stringers, and means retaining the pull against displacement from said turret portion.

2. A lock slider for separable fastener stringers, said slider comprising a channelled body having spaced walls joined at one end in a connecting web, one wall of the slider having centrally thereof an outwardly extending pivot pin, said wall in spaced relation to the pin having an aperture opening into the channel of the slider body, a lock element pivotally enclosing and covering said pin, said element having a finger extending through the aperture to enter the channel of the slider, tensional means engaging the lock element to normally support the finger in the channel, said lock element having an outwardly extending turret portion into which said pin extends, a pull rotatably mounted on the turret portion in operating the slider in two directions on stringers, and means retaining the pull against displacement from said turret portion, a snap fastener socket mounted in the turret portion, and a characterized member having a stud part engaging said socket in detachable mounting of said member.

3. A lock slider for separable fastener stringers, said slider comprising a channelled body having spaced walls joined at one end in a connecting web, one wall of the slider having centrally thereof an outwardly extending pivot pin, said wall in spaced relation to the pin having an aperture opening into the channel of the slider body, a lock element mounted for pivotal movement on said pin, said element having a finger extending through the aperture to enter the channel of the slider, tensional means engaging the lock element to normally support the finger in the channel, said lock element having an outwardly extending turret portion, a pull rotatably mounted on the turret portion in operating the slider in two directions on stringers, means retaining the pull against displacement from said turret portion, a snap fastener socket mounted in the turret portion, a characterized member having a stud part engaging said socket in detachable mounting of said member, and said lock element having downwardly extending rounded pivot portions disposed at opposite sides of said pivot pin.

4. A lock slider for separable fastener stringers, said slider comprising a channelled body having spaced walls joined at one end in a connecting web, one wall of the slider having centrally thereof an outwardly extending pivot pin, said wall in spaced relation to the pin having an aperture opening into the channel of the slider body, a lock element mounted for pivotal movement on said pin, said element having a finger extending through the aperture to enter the channel of the slider, tensional means engaging the lock element to normally support the finger in the channel, said lock element having an outwardly extending turret portion, a pull rotatably mounted on the turret portion in operating the slider in two directions on stringers, means retaining the pull against displacement from said turret portion, a snap fastener socket

mounted in the turret portion, a characterized member having a stud part engaging said socket in detachable mounting of said member, said lock element having downwardly extending rounded pivot portions disposed at opposite sides of said pivot pin, and said lock element having a conical aperture around the pin providing swinging movement of the element on said pin.

5. A lock slider for separable fastener stringers, said slider comprising a channelled body having spaced walls joined at one end in a connecting web, one wall of the slider having centrally thereof an outwardly extending pivot pin, said wall in spaced relation to the pin having an aperture opening into the channel of the slider body, a lock element mounted for pivotal movement on said pin, said element having a finger extending through the aperture to enter the channel of the slider, tensional means engaging the lock element to normally support the finger in the channel, said lock element having an outwardly extending turret portion, a pull rotatably mounted on the turret portion in operating the slider in two directions on stringers, means retaining the pull against displacement from said turret portion, a snap fastener socket mounted in the turret portion, a characterized member having a stud part engaging said socket in detachable mounting of said member, said lock element having downwardly extending rounded pivot portions disposed at opposite sides of said pivot pin, said lock element having a conical aperture around the pin providing swinging movement of the element on said pin, and means retaining the element against displacement from the pin.

6. In lock sliders for fastener stringers, a channelled slider body, a lock element on said slider body for locking the same to said stringers, means comprising a pin on the slider body and a pin-receiving recess in the lock element for pivotally mounting the latter on the pin, said recess being defined by inclined walls for enabling the lock element to pivot on the pin, means retaining the lock element from displacement from the pin, said lock element having a tubular turret portion extending above the pin and into the lower portion of which said pin projects, a ring like pull rotatably mounted on said turret portion, and a characterizing member mounted in the upper portion of said turret portion.

7. In lock sliders of the character described comprising a channelled slider body and a lock element therefor, the combination therewith of a pin on the slider body for pivotally mounting the lock element thereon, means retaining the lock element from displacement from the pin, said lock element having a tubular turret portion extending above the pin and into the lower portion of which said pin projects, a ring like pull rotatably mounted on said turret portion, a characterizing member mounted in the upper portion of said turret portion, and means for keying said member to the turret portion.

8. A lock slider comprising a channelled slider body, one wall of the body having an aperture opening into the channel of said body, a lock element having a projecting lock finger, a post on said wall for receiving the lock element, means on the lock element adjacent the post and in contact with said wall for movably supporting the lock element for seesaw movement on the wall, said lock finger during said movement being movable into and out of the channel of said slider body, said lock element having an outwardly extending hollow portion into which said post ex-

tends, a pull rotatably mounted on said hollow portion for variably positioning a fingerpiece part of the pull to operate the slider, and means for retaining the pull against displacement from said lock element.

9. A lock slider of the character described comprising a channelled slider body, one wall of the body having an aperture opening into the channel of said body, a lock element having a projecting lock finger, means for pivotally supporting said element at a central portion of said wall to enable said finger to be moved into and out of said channel, said lock element having an outwardly extending hollow portion, a pull rotatably mounted on said hollow portion for variably positioning a fingerpiece part of the pull relatively to the ends of the slider to operate the slider, means for retaining the pull against displacement from said hollow portion, a characterized member for disposition on said hollow portion, and means on said member and within the hollow portion for detachably mounting the member thereon.
10. A lock slider of the character described comprising a channelled slider body, one wall of the body having an aperture opening into the channel of said body, a lock element having a projecting lock finger, means movably supporting said element on said wall of the slider to move said finger into and out of the channel of said slider body, said means having rounded surfaces for supporting the lock element for seesaw movement on the said wall, a spring seating in the slider body and operating upon the lock element to normally support said finger in operative position within said channel, said lock element having an outwardly extending hollow portion, a pull rotatably mounted on said hollow portion for positioning a fingerpiece part of the pull at either end of the slider, means for retaining the pull against displacement from said lock element, a characterized member adapted for mounting on said hollow portion of the lock element, means on said member and within the hollow portion for detachably mounting the member thereon, said last named means comprising stud and socket parts, and means on said member and said hollow portion for keying said member in predetermined position.

11. A slider for separable fastener stringers having a post on one wall thereof, a lock element pivotally mounted on and enclosing said post and adapted to lock the slider to said stringers, an outwardly extending hollow portion on the lock element into the bottom of which said post extends and the top of which is open, means in the hollow portion for securing the lock element to said post, a pull secured to the outer side of said hollow portion, and a characterizing member for the slider extending into said hollow portion through the open top.
